UNITED STATES PATENT OFFICE.

THOMAS R. THURBER, OF STOCKTON, CALIFORNIA.

ENGINE.

No. 928,715.

Specification of Letters Patent. Patented July 20, 1909.

Application filed March 1, 1907. Serial No. 360,032.

To all whom it may concern:

Be it known that I, THOMAS R. THURBER, a citizen of the United States, and residing at 733 East Chatnel street, in the city of Stockton, county of San Joaquin, and State of California, have invented certain new and useful Improvements in Engines; and I do hereby declare the following to be a full, clear, and exact description of the said invention, such as will enable others skilled in the art to which it most nearly appertains to make, use, and practice the same.

This invention relates to improvements in engines, and particularly to engines of the internal combustion type.

In the present state of the art, the four cycle type seems to be the preferred practice in this class of engine, in which one or an even multiple of pistons exert torque on a crank shaft. The prime disadvantage in this principle is the fact that at the initial expansion of the gas the crank pin is at a point in its cycle presenting a diminished leverage. When the crank presents its maximum leverage, the gases are greatly diminished in power, and past this center the leverage and the expansion both diminish. The result is scarcely thirty degrees of power stroke for two revolutions, and this with a very inconstant torque. The actions of suction, compression, expansion and exhaustion of the gas require four cycles of the crank shaft, three of which are a retard load on the crank. The ultimate power of a four cycle engine, therefore is only about thirty degrees of rotation in every two revolutions of the crank shaft, necessitating a heavy fly wheel in which to store momentum to carry the load between the power strokes. These disadvantages are in a degree overcome by multiplying the number of pistons acting upon the crank shaft, but the power of the cylinder is in no way increased.

The objects of this invention are to provide a stationary substitute with a constant angle of torque for the crank shaft, and revolve the cylinders about it, thus eliminating the fly wheel; to so arrange the working base that each cylinder completes the four acts of suction, compression, expansion and exhaustion of the gas every revolution; to so

arrange the working centers that each suction stroke completely fills the whole working area of the cylinder and each exhaustion of the burned gas is complete, while the compression stroke is reduced in length to obtain only the compression required.

Other objects and advantages will be made manifest as the description progresses.

In the drawings: Figure 1—is a vertical cross section of an engine constructed in accordance with this invention, certain of the mechanisms being shown in full lines, or only partly in section, to better disclose their construction or function. Fig. 2—is an end elevation of the same with portions broken away to disclose underlying mechanisms.

Broadly the invention consists of a multiplicity of cylinders revolving about a fixed cam whose contour conforms to the planetary and longitudinal travel of the pistons within the cylinders. Excepting certain details of adaption, the ignition and valve systems do not depart from the usual practice in this art.

In detail the invention consists of the driving shaft #1 journaled in the pillars #2 and #3, on the base #4. The cam cylinder #5 is fixed to the pillar #2 and remains stationary, while the shaft revolves in the center. To insure steadiness of action, it is well to provide a suitable shaft-bearing within the cam cylinder for the reception of the shaft. This, however, is not necessary if the pillar support is sufficiently rigid. The flange #6 is keyed, or fixed, to the shaft at #7. The cylinders #8—#9—#10 and #11 are bolted to this flange and revolve therewith. To offset the rending action of centrifugal force, the heads of the cylinders #12 are ground into sockets formed in the ends of the spider #13, which is centered on the shaft #1 and bolted to the flange #6.

To counteract the rotation of the piston, due to its thrust against the wall of the cam slot, I employ a guide 17 formed of a casing 18 secured to the cylinders and mounted to rotate therewith, said casing being provided with slots 20 arranged to receive lateral extensions 19 carried by the crossheads 16 secured to piston rods 15, which latter are, in turn, secured to pistons 14. The crossheads are provided with the stud pins #21, which

are provided with suitable friction reducing contact with the cam channel #22*, sunken into the periphery of the cam cylinder #5. This cam channel represents the path of the

5 reciprocation of the pistons in the cylinders in their orbit about the fixed cam cylinder. The cam slot is plotted to meet the exigencies of the piston action.

As illustrated, the cylinder #8 has just 10 "fired" and is passing over the center into the expansion stroke. The studs following the contour of the cam will rotate their respective cylinders forward. The cylinders being all fixed upon the flange #6, revolve in 15 unison: the flange being keyed to the driving shaft at an angle of 90°, this fixes the angle of torque at a constant angle of 90° and the time of exerted power a full 25% of the revolution with a cam plotted as illustrated. The 20 advance of cylinder #8 to the position of #9 has advanced #9 to the full exhaust position of #10; has advanced #10 to the full suction of #11, and advanced #11 to the expansion position from which #8 started, so that each 25 cylinder in turn takes the full four actions every revolution.

In the drawings four cylinders have been shown to better illustrate the timing of the several positions. In practice an uneven multiple of cylinders is preferable because no two cylinders can then be upon the "dead centers", or turning points, in the cam channel. The number of cylinders, odd or even, is optional.

30 35 The inlet valves #20 are operated by the twin cam inclines #22 on the plate #23, fixed on the pillar #3. The stems #24 are provided with the rollers #25 which ride the cam surface causing the stem to follow the contour 40 thereof under the influence of the spring #26, of suitable design. The valve #20 seats in the opening #27, formed in the spider #13, closing this passage in the intervals of cam action. The opening #27 is the outlet into 45 the cylinder of a passage #28 cored in the spider and communicating with the hollowed portion #29 of the driving shaft. The gas mixture is sucked from the carburetor #32 through the tube #33 extending into the hollow shaft. The cylinder #11 has completed 50 the suction stroke, its intake and exhaust valves are both closed at the cylinder head, and the compression stroke is commencing. Just before reaching the position of cylinder 55 #8, the spark plug #34 makes contact with the commutator brush #35 which discharges the ignition spark within the cylinder "firing" the compressed mixture. Cylinder #9 has completed the expansion stroke, and the exhaust valve 39 is opened by the cam as described and the burned gases permitted to escape into the muffler #36, which consists of a concentric perforated tube into which the several exhaust valves discharge; the gases

escaping to the atmosphere through the perforation #37 by which they are split up sufficiently to deaden the detonation of the sudden drop to atmospheric pressure.

65 The heat due to the combustion of the gases is radiated through the cylinder walls 70 and absorbed by the atmosphere. To facilitate this radiation the exterior of the cylinders is provided with the fin flanges #38 which preferably extend spirally around the cylinders. The spirals are set to cause the 75 air to pass around the cylinders and discharge at the base thereof, whereby the cold air is attracted to the head of the cylinder, the hottest part; therefore requiring the coldest air. In case the engine is placed in a 80 motor car, the cylinder heads should be placed forward for the same reason.

The carburetor, (which requires no detailed description,) may be placed in any convenient location and is capable of varying the 85 mixture, throttling etc. as is common practice.

Any ignition system may be used in conjunction with this invention, that is suitable to the purpose. While the electric system is 90 shown, others may be substituted, such as the ignition by spontaneous combustion induced by high compression etc.

95 While I have shown and described my invention in the class of internal combustion engines of the rotary air cooled type, I do not wish to be understood as confining myself to this class. It is obvious that with suitable modifications well within the spirit of my invention, any expansive fluid may be introduced into the cylinders and accomplish the desired result. The cylinders may be held stationary and the cam cylinder revolved with the shaft. Because of the parallel travel of the piston rods, stuffing boxes 105 may be introduced and the pistons made double acting, or compounded.

110 Having thus described this invention what is claimed and desired to secure by Letters Patent is:—

115 1. An engine of the character described comprising a shaft, a plurality of cylinders each removably secured to said shaft, a piston for each cylinder, a stationary cam having a contour conforming to the longitudinal and planetary travel of said pistons, said cam being provided with a peripheral channel, a crosshead for each piston, said crossheads being provided with lateral extensions, guides for said crossheads provided with slots to receive said extensions, and a stud secured to each piston and working in said cam channel.

120 125 2. An engine of the character described comprising a shaft, a cored spider mounted on said shaft and provided with sockets, a carburetor communicating with said spider, a plurality of cylinders having their heads secured in said sockets, a flange carried by

said shaft and supporting the opposite ends of said cylinders, an annular muffler also formed with said spider, a piston for each cylinder, and means engaged by said pistons for imparting a rotary movement to said spider.

In testimony whereof, I have hereunto set

my hand this twenty-ninth day of January, 1907:

THOMAS R. THURBER.
